UNITED STATES PATENT OFFICE.

HORACE J. CHANDLER, OF DUMMER, NEW HAMPSHIRE.

RUNNING-GEAR FOR SLEIGHS.

SPECIFICATION forming part of Letters Patent No. 655,821, dated August 14, 1900.

Application filed January 27, 1900. Serial No. 3,019. (No model.)

To all whom it may concern:

Be it known that I, HORACE J. CHANDLER, a citizen of the United States, residing at Dummer, in the county of Coos and State of New Hampshire, have invented a certain new and useful Running-Gear for Sleighs, of which the following is a specification.

My invention relates to sleighs, and has for its object to improve the running-gear thereof, so that any inequalities of the ground will be provided for without inconvenience to the occupants of the vehicle.

With this object in view my invention consists in the parts and combination of parts, as will be more fully set forth in the following description, recited in the claims, and illustrated in the accompanying drawings, in which—

Figure 1 is a side elevation of a sleigh constructed in accordance with my invention. Fig. 2 is a front elevation of the same. Fig. 3 is a top plan view of the running-gear. Fig. 4 is an enlarged detail sectional view of the means for securing the front portion of the body to the running-gear; and Fig. 5 is an enlarged plan view of a portion of the rave, axle, and braces.

Referring now to the drawings by reference-numerals, 10 designates runners of a sleigh, 30 and 11 the raves. The raves and runners are substantially braced by the standards 12 and the cross-rods 13, having their ends bent into the form of angle-irons 14, and the rear portion of the running-gear is braced by a single 35 brace 15. Intermediate their ends the raves are provided each with a suitable opening 16, having flared ends, so that an oscillating motion of the axle or rod 17 can take place after being secured therein by means of a nut 18 and collar 19. This axle or rod is connected to the two raves in the manner described, and journaled to and extending in a parallel plane with the axle are the short brace-rods 20 and 21, and projecting from the runners 40 are the braces 20^a and 21^a. The short braces are secured to the raves by suitable bolts 22, and the braces 20^a and 21^a are secured to the runners in a like manner. A bar 23 connects the forward portion of the raves and is provided with a core of metal 24, to which is se-

cured an eyebolt 25, connected to the body of the sleigh by a nut 26.

27 is a transverse bar to which the thills are secured.

Resting on the axle 17 and secured thereto 55 are the springs 28 and 29, adapted to take up the unevenness of the runners owing to the inequality of or obstacles on the ground.

By reference to Fig. 2 it will be seen that should the left-hand runner strike an obstruction 60 it will be raised against the spring 28 without affecting the relative position of the body of the sleigh, and by reason of the peculiar construction of bracing and connecting the various parts the sleigh will be greatly 65 improved.

Having thus fully described my invention, what I claim as new, and desire to obtain by Letters Patent of the United States, is—

1. In a sleigh, the combination with the 70 raves each of which is provided with openings having flared ends, and the axles are each provided with a shoulder for engaging with the inner side of the rave and with a nut for engaging with the outside, of diagonally-arranged braces extending from a point on the axle at a distance from the rave, to the raves and to the runners respectively, to the front and to the rear of the axles. 75

2. In a sleigh, the combination with runners, standards and raves, of diagonally-arranged braces between the standards, the ends of which are bent into an angle and secured to the runners and to the raves respectively, and diagonally-arranged braces extending from the axles to the raves and to the runners respectively. 80

3. In a sleigh, the combination with a frame, the runners of which are vertically movable relatively to each other, of a bar secured at 90 its ends to the forward part of the raves, an eyebolt secured upon the central portion of the bar against lateral movement, a spring upon each end of one of the axles, and a body secured to the springs and to the eyebolt. 95

HORACE J. CHANDLER.
